UNITED STATES PATENT OFFICE.

FREDERICK W. MARTIN, OF NEW YORK, N. Y., ASSIGNOR TO FRANKLIN RAILWAY SUPPLY COMPANY, OF WILMINGTON, DELAWARE, A CORPORATION OF DELAWARE.

AUTOMATIC DRIVING-BOX WEDGE.

1,268,781.

Specification of Letters Patent. Patented June 4, 1918.

Application filed September 1, 1917. Serial No. 189,294.

To all whom it may concern:

Be it known that I, FREDERICK W. MARTIN, of the borough of Queens, county of Queens, in the city and State of New York, have invented a certain new and useful Improvement in Automatic Driving-Box Wedges, of which improvement the following is a specification.

This invention relates to means for taking up wear between driving boxes and the pedestals of locomotives; and has for its object to provide an improved wedge device for this purpose which shall operate automatically to take up wear and keep the parts tight, but at the same time have sufficient freedom of sliding movement to allow for the usual spring action and the vibration of the axle-box in the frame, without any binding or sticking of the wedges.

In the accompanying drawing, Figure 1 is a side elevation with one half of the driving box and my improved wedge device indicated in vertical section; Fig. 2 is a horizontal section taken on the line 2-2 of Fig. 1; and Fig. 3 is a similar horizontal section showing a modification.

According to the construction shown, the driving box 6, having flanges 7 and 8, is mounted between the pedestal jaws 4, and 5, the face of the jaw 4, being inclined to cooperate with the face of the adjusting wedge 9, which is forced upward by the action of the spring 12. The other face of the wedge 9 is vertical.

The face of the driving box is inclined slightly in the direction opposite to the face of the pedestal 4, and is engaged by the correspondingly inclined face of the wedge 13, the opposite face of which is vertical. Wedge 13 is provided with lugs 18 and 19 at top and bottom, respectively, having a slight clearance with the top and bottom of the driving box. Between the vertical faces of the wedges 9 and 13 is located the parallel-sided floating plate 10, of such length as to have a slight clearance between the frame 17 at the top, and the binder 16 at the bottom.

The adjusting wedge 9 may be guided either by separate strips 11 bolted to the pedestal jaw, as shown in Fig. 2, or by integral flanges 11^a formed on the wedge, as indicated in Fig. 3.

The action of the spring 12 presses the

wedge 9 upward taking up all wear of the parts and keeping the driving box snug in the pedestal but at the same time there will be no tendency for the parts to stick and interfere with the free spring action or movement between driving box and frame. When there is an upward movement of the driving box relative to the frame it has a tendency to loosen the wedge 13, until it comes in contact with the stop lug 18, after which wedge 13, will move with the box sliding upon the floating plate 10. When there is a downward movement of the box relative to the frame it will carry wedge 13 and floating plate 10 with it to the extent of the clearance between the lower end of the plate and the binder. This movement will also be transmitted to wedge 9, tending to pull it down slightly or sufficiently to relieve the same and prevent sticking. These two movements keep the wedge device free and prevent any tendency to stick or bind.

Having now described my invention what I claim as new and desire to secure by Letters Patent, is:

1. The combination with a pedestal jaw having an inclined face, of a driving box having a face inclined in the opposite direction, wedges engaging said inclined faces, and a floating plate between said wedges.

2. The combination with a pedestal jaw having an inclined face, of a driving box having a face inclined in the opposite direction, a spring actuated adjusting wedge engaging the pedestal jaw, and a wedge having stop lugs with clearance for engaging the driving box.

3. The combination with a pedestal jaw having an inclined face, of a driving box having a face inclined in the opposite direction, wedges each having one inclined and one vertical face, and a vertical sided floating plate located between said wedges.

4. The combination with a pedestal jaw having an inclined face, of a driving box having a face inclined in the opposite direction, wedges engaging said inclined faces, and a floating plate between said wedges and of such length as to have a slight clearance between the frame at the top and the binder at the bottom.

In testimony whereof I have hereunto set my hand.

FREDERICK W. MARTIN.
